DESIGN FOR AN IRONER

Raymond E. Patten, Bridgeport, Conn., assignor
to General Electric Company, a corporation of
New York

Application November 23, 1934, Serial No. 54,130

Term of patent 3½ years

To all whom it may concern:

Be it known that I, Raymond E. Patten, a citizen of the United States, residing at Bridgeport, in the county of Fairfield, State of Connecticut, have invented a new, original, and ornamental Design for an Ironer, of which the following is a specification, reference being had to the accompanying drawing, forming a part thereof.

Fig. 1 is a perspective front view of an ironer showing my new design.

Fig. 2 is a perspective end view of the ironer shown in Fig. 1.

I claim:

The ornamental design for an ironer, substantially as shown.

In witness whereof I have hereunto set my hand this 20th day of November, 1934.

RAYMOND E. PATTEN.
